F. J. BRYANT

MOVABLE HOISTING DEVICE

Filed April 3, 1920

Patented May 15, 1923.

1,454,881

UNITED STATES PATENT OFFICE.

FRANK J. BRYANT, OF WEST BROOKFIELD, MASSACHUSETTS.

MOVABLE HOISTING DEVICE.

Application filed April 3, 1920. Serial No. 371,040.

To all whom it may concern:

Be it known that I, FRANK J. BRYANT, a citizen of the United States, residing at West Brookfield, in the county of Worcester and 5 State of Massachusetts, have invented a new and useful Movable Hoisting Device, of which the following is a specification.

This invention relates to a hoisting device or small crane for use in factories, garages, 10 and other places where heavy parts have to be lifted out of machines and set into them. It is particularly adapted for use in the ordinary automobile garage for lifting out the motor and other parts and replacing 15 them.

The principal objects of the invention are to provide a crane or hoisting device of that character formed of structural iron parts and therefore capable of being made very 20 strong without heavy expense; to provide novel constructions for joining the structural iron parts in such a way as to produce very strong joints; to provide a construction which will permit of the moving of the 25 suspended vertically movable load along an I beam or like track at the top in one direction; and to provide for the movement of the entire hoisting device in a direction at right angles thereto, thus providing universal motion of the load.

Further objects and advantages of the invention and features of construction will be described below.

Reference is to be had to the accompanying drawings, in which—

Fig. 1 is a side view of a hoisting device constructed in accordance with this invention;

Fig. 2 is an end view with the top track 40 in section on the line 2—2 of Fig. 1;

Fig. 3 is a side view of a part of one of the joints;

Fig. 4 is a horizontal sectional view of the same on the line 4—4 of Fig. 3;

Fig. 5 is a vertical central sectional view of the upper end of the supporting upright at one end of the hoisting device;

Fig. 6 is a sectional view of the cast block which is inserted to form a part of the joint 50 on the line 6—6 of Fig. 3.

Fig. 7 is a plan of one end of the base and castor support;

Fig. 8 is a sectional view thereof on the line 8—8 of Fig. 7 and showing the castor 55 in inoperative position, and

Fig. 9 is an end view of a modification.

The invention is shown as comprising two up-rights 10 and 11, constituting the entire supporting structure, formed of ordinary iron piping. Each of these is mounted on 60 a horizontal base 12 having side flanges 12^a, a U-bar being used preferably. The pipe is bolted or riveted to these two side flanges at their center and rests on the bottom web. Braces 13 are shown riveted to the pipe 65 above and to the base below.

In order to make the hoisting device readily movable in what may be considered a transverse direction each base is provided with a slot at 14 at each end. Back of this 70 is a hinge rivet 15 above the bottom of the base 12 and on this rivet is pivotally mounted a frame 16. This frame has a shaft 17 passing through it with a wheel or castor 18 freely rotatable on the shaft and located in 75 a slot 19 in the frame. The frame 16 is provided with a loose pin 20 which is adapted to pass through perforations in the sides 12. When the parts are in the position shown at the left of Fig. 2, the pin 20 is in place 80 in the perforations and the wheel or castor 18 extends below the bottom of the U-bar constituting the base 12. When all four castors 18 are in this position, the four pins 20 positively hold them there and thus there 85 are four castors or rollers on which the entire device can be moved about. However, if it is not desired to use the castors the four pins 20 are withdrawn and then the bases rest on their own lower surfaces and the castors 90 are rendered inoperative for the time being. They simply rest by gravity on the floor as shown in Fig. 8.

The up-rights 10 and 11 support at the top an I-beam 21 on which runs a roll 22, 95 provided with a wheel 23 preferably provided with teeth and carrying a shackle 24 suspended from the axis thereof. A chain 25 is used as is well understood for moving this device along the I-beam, and supporting 100 the load which can be carried back and forth in this way and lifted.

The method of connecting the I-beam with the up-right pipes 10 and 11 constitutes an 105 important feature of this invention. For this purpose, the upper end of the pipe 10 is shown as provided with a vertical slot 30 opening down from its end. This is the only modification required in the pipe except that perforations 31 are put through for the 110

- reception of a bolt or pin. The end of the I-beam at the bottom is modified by sawing off the bottom flange along the line 32 across the I-beam and sawing off the web horizontally at a plane just above the lower flange so that the end of the lower flange is entirely removed. The object of this is to permit the web to be inserted in the slot 30 and the top of the pipe to support the lower 5 surface of the upper two flanges on the I-beam. Preferably the top of the pipe is shaped away on a slant at 33 to fit the slanting lower surfaces of the upper flanges of the I-beam.
- 15 An additional element is introduced here consisting of a pair of semi-cylindrical filling blocks 34 which may be in the form of simple castings introduced on the two sides of the web of the I-beam to fill in the space 20 between the web and the internal surface of the pipe. They are preferably perforated at 35 to receive bolts or rivets 36 to fasten the parts together. Although these two semi-cylindrical blocks, can be made separately and extend merely from the lower surface of the upper flange of the I-beam to the bottom thereof, they are made more stable by forming them in one piece as a single casting extending down as shown in 25 Fig. 3 below the bottom of the I-beam. Thus the solid cylindrical part 37 will extend down into the pipe a distance below the I-beam commensurate with the height of the I-beam. This is the preferred construction 30 and a third bolt 38 is passed through this part 37 of the filling block, thus furnishing a guide firmly secured both to the I-beam and to the pipe for preventing the joint between the two from working back and forth.
- 35 40 In fact, this furnishes an extremely strong joint capable of resisting all pressure to which it may be subjected in ordinary usage.
- The other end of the hoisting device can 45 be formed in exactly the same way and as that is obvious, I have introduced a modification into the drawings by arranging the other end for adjustment which under some conditions is desirable. For this purpose, 50 the pipe 11 is split diametrically at 40 for a considerable distance down from its upper end. The two upper ends thus formed are shaped by proper processes to provide jaws 41 for gripping the lower flange of the I-beam, to prevent the parts getting out of 55 alignment. A bolt 42 is passed through the two halves of the pipe just below the I-beam to clamp the two halves together against the opposite ends of the lower flange. By loosening the bolt, the position of the up-right 60 11 can be changed as indicated in dotted lines in Fig. 1 for any purpose which may be desired such as avoiding machinery located below.
- 65 It will be seen that the invention constitutes a simple, convenient and comparatively inexpensive small crane, suitable for use in many places and that the joints between the I-beam and pipes are rigid but easily removable, and that a simple convenient way is provided for making the whole device translatable in a direction transverse to the direction in which the load is moved on the crane itself. By utilizing well known structural iron shapes easily obtained in the market a very great saving is secured.
- In the form shown in Fig. 9 the pipe 11 is not split but left solid and clamping plates 45 are secured on opposite sides by bolts 46 to hold it firmly to the I-beam 21.
- Although I have illustrated and described only a single form of the invention, I am aware of the fact that modifications can be made therein by any person skilled in the art without departing from the scope of the invention as expressed in the claims.
- Therefore I do not wish to be limited to all the details of construction herein shown and described, but what I do claim is:—
1. In a device of the character described, the combination with a pair of up-rights, each consisting of a piece of pipe, and a horizontal I-beam at the top, one of said pipes being split down at the top diametrically to provide jaws for securing it to the lower flange of the I-beam, of removable means for holding said jaws clamped against said flange whereby said up-right can be moved along the flange.
2. In a device of the character described, the combination with an up-right consisting of a piece of pipe, of a horizontal I-beam at the top, the I-beam constituting a track for a lifting device, and having the end of its lower flange cut away to receive the pipe, the upper end of said pipe being provided with a slot for receiving the web of the I-beam so that the upper flange will rest on top of said pipe.
3. In a device of the character described, the combination with an up-right consisting of a piece of pipe, and a horizontal I-beam at the top, the I-beam constituting a track for a lifting device, and having the end of its lower flange cut away to receive the pipe, the upper end of said pipe being provided with a slot for receiving the web of the I-beam so that the upper flange will rest on top of said pipe, and a filling piece between the web and the pipe fitting against the surface thereof and extending below the I-beam to guide the I-beam with respect to the pipe and prevent a rocking motion at the joint.
4. In a device of the character described, the combination with a pair of up-rights, each consisting of a piece of pipe and a horizontal I-beam at the top, the I-beam constituting a horizontal track for a lifting device, and having at the end its lower flange cut away to receive the pipe, the upper end

of said pipe being provided with a slot for receiving the web of the I-beam so that the upper flange will rest on top of said pipe, a filling piece between the web and the pipe 5 extending below the I-beam to prevent a rocking motion at the joint, means extending through the pipe, filling piece, and web for holding the pipe and I-beam together, and means also extending through the pipe 10 and filling piece below the I-beam for the same purpose.

5. In a device of the character described,

the combination with a pair of up-rights, consisting of a piece of pipe and a horizontal I-beam at the top, of a joint rigidly supported thereby, one of said pipes having jaws for securing it to the lower flange of the I-beam, and removable means for holding said jaws clamped against said flange whereby said up-right can be moved along 15 the flange.

In testimony whereof I have hereunto affixed my signature.

FRANK J. BRYANT.
